 Borg-Warner Corporation, a corporation of
 Illinois

Application June 7 1937, Serial No. 146,787

4 Claims. Cl. 38—59

This invention relates to ironing apparatus and has particular reference to power operated roll type ironing machines useful for ironing and pressing fabrics or other materials.

5 In the drawings there are illustrated several forms of ironing machines embodying my invention and which in general comprise a support including a power transmission mechanism, an ironing shoe mounted upon the support, an ironing roll mounted upon the support and adapted to be rotated, the shoe and the roll being adapted to be brought into operative engagement for ironing or pressing and the transmission being provided with suitable mechanism and controls 10 for moving the ironing shoe and the roll into and out of engagement and for driving the roll while the same is in engagement with the shoe.

A principal object of the invention is to provide a new and improved form of ironing apparatus.

Another object of the invention is to provide a new and improved form of ironing apparatus wherein the roll is adapted to be rotated and to be oscillated for bringing the same into and out 25 of operative engagement with the ironing shoe.

Another object of the invention is to provide a new and improved form of power transmission mechanism for roll ironing apparatus.

Another object of the invention is to provide 30 a new and improved form of support and driving connection for a movable roll type of roll ironing apparatus.

Another object of the invention is to provide 35 a novel form of power operated roll ironer which is more efficient in operation and which is of a simpler construction than roll ironers of the type now being manufactured.

Other objects and advantages of the invention 40 will be apparent from a consideration of the following specification taken in conjunction with the accompanying drawings of which there are five sheets and wherein:

Fig. 1 is a perspective view of an ironing apparatus embodying my invention;

45 Fig. 2 is a plan view, partially in section, of part of the transmission mechanism and taken generally in a plane on the line 2—2 of Figs. 1 and 4;

50 Fig. 3 is a vertical sectional view through the transmission, taken generally in a plane on the line 3—3 of Figs. 2 and 4, looking in the direction of the arrows, and illustrating part of the roll oscillating or shifting mechanism;

55 Fig. 4 is a vertical sectional view through the

transmission and roll support and taken generally in a plane along the line 4—4 of Fig. 6;

Fig. 5 is a vertical sectional view through the ironing roll taken generally in a plane on the line 4—4 of Fig. 6 and forms a continuation of 5 Fig. 4;

Fig. 6 is a vertical sectional view taken generally in a plane on the line 6—6 of Fig. 2, looking in the direction of the arrows, and illustrating in addition to part of the roll driving mechanism of the 10 transmission, the mounting for the ironing shoe and the ironing roll in pressing or ironing engagement with the ironing shoe;

Fig. 7 is a view similar to Fig. 3 but illustrating the eccentric of the roll oscillating mechanism in the position in which it is disposed when the ironing roll is separated from the ironing shoe;

Fig. 8 is a vertical sectional view through the transmission, taken generally in a plane on the 20 line 8—8 of Fig. 2 and illustrating the roll shifting mechanism and the control therefor;

Fig. 9 is a vertical sectional view through part of a transmission and ironing roll and illustrating a modified form of the invention; and 25

Fig. 10 is a view similar to that of Fig. 9 and illustrating a further modified form of the invention.

In Fig. 1 of the drawings there is illustrated in perspective an ironing apparatus of the roll type which includes a support 20, a transmission indicated generally at 22, an ironing roll 24 supported from the housing of the transmission 22, an ironing shoe 26 mounted upon an arm 28 carried by the support 20, a control member 30 35 which is operable for controlling the operation of the ironing apparatus and a second control member 32 which is operable for changing the speed at which the roll is driven, or for disconnecting the roll from its driving mechanism so 40 that the ironer may be operated for pressing.

The transmission 22, as illustrated, comprises a housing which includes an open-ended supporting member 34 rigidly secured to the support 20 in any suitable manner, a bearing plate 36 for 45 closing the end of the compartment 38 within the housing within which the transmission mechanism is disposed, said bearing plate being detachably and rigidly secured to the end face of 50 the support member 34 such as by a plurality of bolts 40, and an ornamental cap 42 which is adapted to cover the bearing plate 36. The ornamental cap 42 may be held in place by a plurality of spring clips 44 carried thereby and 55 which are engageable with apertured portions of

the bearing plate 36. The housing of the transmission may extend below the surface of the support or table 20 to provide a space or compartment 46 open at the bottom end in which a motor 48 for operating the ironer may be arranged. The motor 48 may be supported by the housing in any suitable or convenient manner.

The shoe 26 preferably is provided with a heating means therein and includes a polished metallic face 50 which is shaped to conform to the padded surface of the roll 24 and is coextensive in length therewith. The shoe 26 is carried by the arm 28 of a channel shaped bell crank lever 54 and to the upper end of which arm 28 the shoe is connected by means of a pivotal connection 56. The pivotal connection may include a horizontally disposed pin 58 passing through aligned openings in the upper end of the arm 28 and in a bracket 60 carried by the shoe 26. A spring clip 62 carried by the pin 58 has one end thereof engaging a portion of the shoe at 64 and the other end thereof engaging a portion of the arm 28 at 66 for resiliently supporting the shoe from the arm in the position illustrated in Fig. 6. The arm 28 of the bell crank extends upwardly through the opening at the rear of the support 20 and midway between the ends of the roll 24. The support 20 may be provided with a pair of spaced downwardly extending brackets 68 carrying a pin 70 on which the bell crank lever 54 is pivotally supported by means of a hub 72 formed integrally therewith. That portion of the bell crank 54 below the surface of the support 20 extends horizontally and may be bifurcated to provide a pair of arms 74. Each arm 74 has associated therewith a coil spring 84 backed up by an adjustable seat 76 provided by a washer held against upward movement by a nut 78 threaded on to a fixed post 80 secured to a bracket 82, for resisting clockwise movement of the bell crank 54 about its pivot 70. A pair of nuts 86 may be threadedly secured to the bottom end of each post 80 and below each of the arms 74 to provide a stop for limiting the counter clockwise movement of the bell crank 54 about its pivot 70. The spring 84 provides a resilient stop for the shoe 26 and is adapted to permit movement of the shoe 26 relative to the roll 24 when the parts are in the position illustrated in Fig. 6 so as to accommodate material of substantial thickness between the surface of the padded roll 24 and face 50 of the shoe 26.

While the shoe is adapted to remain substantially in the position illustrated in Fig. 6 or 7, the pivotal connection 56 between the shoe 26 and its supporting arm 28 is such as to permit the shoe to be turned in a clockwise direction about the pin 58 to a position where the face of the shoe is disposed upwardly or in a substantially horizontal position so as to permit the shoe to be used for steaming purposes. The pivotal connection 56 between the shoe 26 and its supporting arm 28 also is such as to permit a slight amount of turning of the shoe 26 about a vertical axis in order that the face of the shoe may be properly applied to the surface of the padded roll 24 particularly under conditions where material is being passed between the shoe and the roll only at one end thereof. As the shoe is supported from a point centrally of the ends thereof, the pressure between the face of the shoe and the surface of the padded roll will be distributed substantially equally over the entire contacting surfaces.

The roll 24 may comprise a cylindrical metal-

lic shell 88 covered substantially by padding 90 of substantial thickness and a smooth piece of fabric 92. One end of the roll may be provided with a circular plate 94 having the outer periphery thereof flanged at 96 and welded or otherwise secured to the inside of the shell 88, while the center of the plate 94 may be flanged inwardly at 98 to provide a seat for a bushing 100 which is secured to flange 98 and is supported for rotation on a bearing 102 by means of which one end of the roll is supported. The bearing 102 is provided by one end of a plug, the other end of which is seated within the end of a tube 104 and fixed thereto. A collar 106 and a nut 108 threaded into a suitable opening in the plug 102 may be utilized for preventing axial separation of the bushing 100 and bearing 102. The tube 104 extends along the axis of the roll 24 and approximately the length thereof. To the other end of the tube 104 (Fig. 4) there is fixedly secured a circular plate 110, the outer periphery of which is flanged to provide an annular bearing 112 which forms a seat for an annular bearing member 114 carried by the roll 24 adjacent the transmission end thereof. The tube 104 is held against rotation, as will be hereinafter explained, and the roll 24 is adapted to rotate upon the tube 104 and the bearings provided thereby.

The housing of the transmission, as illustrated in Figs. 2 and 4, is provided with an annular boss 116 which forms a socket or rigid seat for a supporting tube 118, one end of which may be press fitted into the bore of the boss 116 and locked therein by means of a set screw 120. The outer end of the tube 118 which may terminate substantially centrally of the ends of the roll 24 and is adapted to provide a bearing seat 121 for an arm or member 122, the lower part of which is arranged to telescope the end of the tube 118 and the upper part of which may be bifurcated as at 124 and which bifurcations are provided with aligned bores 126 for receiving the tube 104 and which tube 104 may be locked to the arm 122 by means of a pair of set screws 128. While the arm 122 is locked to the tube 104, the arm 122 is free to oscillate about the tube 118.

A roll oscillating tube 130 extends through the tube 118 and at one end thereof is seated within a bore in the arm 122 and locked thereto by means of a set screw 132 while at the other end, said oscillating tube 130 is seated in a bushing at 134 arranged within the end of the tube 118. The tube 130 is adapted to be oscillated, as will hereinafter be explained, for moving the roll 24 toward and away from the shoe 26. While the roll will rotate about the axis of the tube 104, the oscillation of the roll about the axis of the tube 130 will cause the surface of the padded roll 24 to move into and out of engagement with the face of the shoe 26.

A roll driving shaft 136 extends axially of the tube 130 and at one end thereof (Fig. 5) is provided with a pinion 138 fixed upon the shaft operatively engaging an internal gear 140 provided by a member 142 which is secured to the shell 88 of the roll for movement therewith, such as by means of one or more screws 144. The hub of the gear 140 may be provided with a bearing member 146 which may be seated upon the outside of the tube 104 so that the gear 140 in effect will rotate upon the tube 104. As the center of oscillation of the roll and the center of rotation of the pinion 138 coincide, the teeth of the

pinion will always be in driving relationship with the teeth of the gear 140.

The roll oscillating tube 130 extends into the mechanism compartment 38 of the transmission housing and has there connected to it a sleeve 146 by means of a set screw 148 so that the sleeve 146 will oscillate with the tube 130. The sleeve is provided with an arm 150 (Fig. 8) connected by means of a pin 152 to a connecting rod 154, 10 the connecting rod 154 being connected to an eccentric 156 rotatable upon a fixed shaft 158. One end of the shaft 158 is seated within a bore in the wall of the transmission housing and the other end of the shaft 158 is supported by the bearing plate 36. The eccentric 156 is formed as 15 a part of a member which includes a hub 160 rotatable upon the shaft 158.

A worm wheel 162 (Fig. 2) driven by a worm 164, provided with a cylindrical hub 166 (Fig. 4), 20 is rotatably mounted upon the shaft 158. The hub 160 of the eccentric 156 and the hub 166 of the worm wheel 162 are adapted to provide a cylindrical clutching surface for a spring clutch 25 which includes a coil spring 168, one end 170 of which is turned radially outwardly to be seated between a pair of lugs 172 provided on a side of the eccentric 156. The other end of the clutch spring 168 is also turned outwardly at 174 and engaged in a notch in a circular plate 176 freely 30 rotatable on the hub 166 of the worm 162 and held in frictional contact with an annular surface 178 on a side of the worm gear 162. The inside diameter of the clutch spring 168 may be finished and may be slightly smaller than the 35 outside diameter of the hub 166 so that there is very slight frictional drag between the two parts during such time as relative movement therebetween takes place. The spring clutch including the parts 168, 166 and 160 comprises a form of a 40 one way or over running friction clutch and operates to transmit torque in one direction only. The plate 176 is provided with a pair of axially extending lugs 180 spaced 180 degrees apart and adapted to be engaged by an end 182 (Fig. 2) 45 of the control member 30.

During such time as the motor 48 is operating, the worm gear 162 will be continuously driven and the eccentric 156 is adapted to be operated under the control of the spring clutch from the continuously operating worm gear 162. As illustrated in the drawings, the spring clutch including the parts 160, 166, 168, 176 and 182 comprises what is commonly known in the art as "an 180 degree clutch," that is, a clutch which 50 will, upon engagement, remain engaged for 180 degrees of rotation and thereafter will automatically disengage. In the case of the spring clutch illustrated herein, the rotation of the worm gear 162 and hub 166 will tend to rotate the plate 176. However, as the end 182 of the control 55 30, by engagement with one of the lugs 180 on the plate 176, holds the same against rotation, the spring 168 will not grip the clutching surface 166 and hence the eccentric 156 will remain stationary. As the spring 168 is coiled in the opposite direction in which the worm gear 162 rotates, rotation of the worm gear 162 will tend 60 to cause the spring 168 to wind up or grip the clutch surface 166 due to the frictional drag between the plate 176 and the side wall of gear 162 and the inside of the clutch spring 168 and clutch surface 166. The control member 30 which is pivoted at 184 to a boss on the inside of the transmission case is adapted upon operation to move 65 the end 182 out from in front of the lug 180,

thereby permitting the plate 176 to be carried around with the worm gear 162 due to the frictional drag therebetween. As soon as the plate 176 begins to rotate with the worm gear 162, the spring 168 will contract and grip the clutching 5 surface 166, thereby coupling the member 168, and the member 166 for driving the member 168 and the eccentric 156. The control member 30 is adapted to be operated simply by pushing the same and immediately thereafter releasing it. As 10 the worm gear 162 is rapidly rotating, the lug 180 will begin to move. As soon as the end 182 of the control member 30 moves out from in front thereof, and as the control member is immediately released after actuation, the end 182 thereof will 15 return to a position in the path of the lugs 180, but the lug 180 with which the end 182 was in contact will have been moved around with the gear 162 and the end 182 of the control 30 will be in the path of the second lug 180 upon the 20 plate 176 thereby permitting 180 degrees rotation of the plate 176. So soon as the second lug 180 comes into contact with the end 182 of the control 30, the clutch spring 168 will unwind or release its grip upon the clutch surface 166 with 25 the result that the eccentric 156 will immediately come to rest and the worm 162 will continue to rotate. Upon each actuation of the control 30, the eccentric 156 will move through 180 degrees of travel and will through the intermediary of the 30 connecting rod or link 154 and the sleeve 146 oscillate the tube 130, arm 122, tube 104 and roll 24 for moving the roll relative to the shoe.

In the position in which the parts are illustrated in Figs. 3 and 4, the roll is in shoe-engaging position; whereas in the position in which the parts are illustrated in Fig. 7, the roll has been shifted away from the shoe. Upon each successive operation of the control 30, the roll will be alternately shifted toward and away from 40 the shoe.

Referring particularly to Figs. 4 and 6, it will be observed that the worm 164 at its upper end is journaled in a bearing 186 and at its lower end is journaled in a bushing 188. The bushing 188 45 is arranged within a bore formed in a wall 190 of the transmission housing and the worm shaft is provided with a shoulder 192 which is adapted to be located by means of a nut 194 threaded into a cooperative part of the wall 190 and rigidly held 50 in place by means of a lock nut 196. The nut 194 and lock nut 196 provide a means for properly locating the worm with respect to the worm gear 162. The coupling 198 operatively connects the shaft of the worm to the shaft 200 of the 55 motor. The motor 48 may be electrically operated under the control of a mechanically operated switch so that during such times as the ironer is not in use, the motor may be stopped.

One side of the worm gear 162 is formed to 60 provide a part 202 of a dog clutch which may be referred to as the roll driving clutch. The other part 204 of the roll driving clutch is formed upon a hub 206 which is provided with a pair of gears 208 and 210, the clutch member 204 and the gears 65 208 and 210 being rotatable as a unit. The hub 206 is adapted to be shifted axially by a fork 212 for the purpose of engaging and disengaging the roll driving clutch or the clutch members 202 and 204.

The roll driving shaft 136 within the transmission is journaled in a bushing 214 pressed into the end of the roll oscillating tube 130 and extends therebeyond where a pair of gears 216 and 218 are mounted thereon for rotation rela- 75

tive thereto. The gears 216 and 218 are in constant mesh with the gears 208 and 210 respectively, and it will be observed that the size of the gears is such as to provide two different driving speeds for the roll driving shaft 136. Clutch member 220 slidably keyed to the roll driving shaft 136 and disposed between the gears 216 and 218 forms part of a dog clutch which is adapted selectively to connect either the gear 216 or the gear 218 to the shaft 136 for driving the same. Gears 216 and 218 are each provided with a dog clutch member 222 cooperable with the clutch member 220 for connecting either of the gears 216 or 218 to the shaft 136. The clutch members 220 and 222, which may be designated as the two speed clutch are adapted to be operated by a fork 224 (Figs. 2 and 6) engageable with the member 220 and slideable upon a rod 226. One end of the rod may be provided with a plurality of notches 228 (Fig. 2) and the shift fork 224 may be provided with a detent 230 for engagement with the notches 228 for locating the positions of the clutch member 220 and holding the same in the selected position. The shift fork 224 is adapted to be operated by the control member 32 which is mounted upon a shaft 232 (Fig. 6) extending through a boss 234 in the front wall of the transmission housing. Within the housing, an arm 236 is pinned to the shaft 232 and carries a pin 238 which extends into a vertical slot in the shift fork 224 for operating the same, so that upon movement of the finger of the control member 32 to the left from the position illustrated in Fig. 2, the shift fork 224 and clutch member 220 are shifted to selectively connect either of the gears 216 or 218 to the shaft 136. One end of the pin 238 may extend into a horizontal slot in the shift fork 224 so as to provide a guide therefor. In this manner the operator may select the speed at which the roll will rotate or may disengage the clutch member entirely so that the roll will remain stationary for pressing purposes or the like.

The shift fork 212 (Fig. 4) which is operable for engaging and disengaging the roll driving clutch 202, 204 is carried by a hub 240 fastened upon a slideable rod 242 mounted for axial movement in a pair of guides 244 formed on the inside of the transmission housing at the top thereof. The shift rod 242 is biased by means of a spring 246 confined between one of the guides 244 and a collar 248 held in place on the rod 242 by a pin 250 for holding the parts 202, 204 of the roll driving clutch in engagement. The connecting rod or link 154 (Figs. 7 and 8) is formed to provide a cam 252 which is adapted to engage one end of the shift rod 242, upon rotation of the eccentric 156, for shifting the shift rod 242 to disengage the parts 202, 204 of the roll driving clutch when the roll is shifted out of ironing relationship with the shoe 26. The spring 246 operates to engage the roll driving clutch when the cam 252 is moved out of engagement with the end of the shift rod 242, which occurs when the roll 24 is being shifted into ironing relationship with the shoe. Thus the roll driving clutch is engaged when the ironing roll is shifted into engagement with the ironing shoe and is disengaged when the roll is shifted out of engagement with the ironing shoe. If one of the gears 216 or 218 is connected to the shaft 136 through the clutch member 220, the roll 24 will be rotated about its own axis when the roll driving clutch is engaged, and the roll will be at rest when the roll driving clutch is disengaged.

In operation, assuming that the motor is operating and that the roll is operated from the shoe as illustrated in Fig. 7, material to be ironed may be laid upon the upper portion of the roll in the proper manner. Operation of the control member 30 will cause the roll oscillating clutch to engage in order to effect the shifting of the roll 24 into ironing relationship with the shoe. As a result of the shifting of the cam 252 during the shifting of the roll 24 into engagement with the shoe 26, the roll driving clutch 202, 204 will be engaged and, assuming the clutch member 220 is connecting one of the gears 216, 218 to the shaft 136, the roll will be rotated about its own axis and cause the feeding of the material to be ironed in between the face of the shoe and the surface of the roll. Subsequent operation of the control member 30 will effect the shifting of the roll out of engagement with the shoe and will also bring about the disengagement of the roll driving clutch.

If it is desired to use the ironing machine for pressing purposes, the control 32 may be operated to disengage the gears 216 and 218 from the shaft 136 so that the roll will not rotate when the same is shifted into press relation with the shoe, even though the roll driving clutch is engaged.

In the modified form of the invention illustrated in Fig. 9, the same transmission mechanism, controls and other parts of the apparatus illustrated in Figs. 1 to 8 may be used, the construction illustrated in Fig. 9 differing from that illustrated in Figs. 1 to 8 in the manner in which the ironing roll is supported and driven. In this modification a tube 318 may be rigidly secured within a socket 320 formed in the housing of the transmission, said tube 318 and the wall of the socket 320 being provided with an arcuate slot through which a pin 322 extends. The pin 322 at its inner end extends into and fits a hole in an oscillating tube 330 and at its outer end is threaded into a sleeve 331 which has a bearing on the outside walls of the socket 320. A plate 332 is rigidly secured to a radially arranged face of the sleeve 331 and at its outer end is formed to provide a bearing 333 upon which one end of the roll 324 rotates and is supported.

The tube 318 extends substantially the entire length of the roll and at its outer end is provided with an internal bushing 334 which forms a bearing for the outer end of the roll oscillating tube 330. A crank arm 335 is pinned to the outer end of the oscillating tube 330 and carries an axially extending member 336 which forms a bearing and support at the outer end of the roll upon which is journaled a bushing 337 carried by an end plate 338 of the roll. The outer end of the oscillating tube 330 is provided internally with a bushing 339 which forms a bearing for the end of a roll driving shaft 340 carrying a pinion 341 which meshes with an internal gear 342 connected to the shell of the roll 324 for driving the same. In this case the supporting tube 318 extends substantially the full length of the roll and the axis of the tube 318 coincides with the axis of oscillation of the roll 324. The roll driving shaft 340 is disposed upon the axis of oscillation of the roll 324 so that the pinion 341 will remain in engagement with the internal gear 342 at all times. The roll driving shaft 340 and the roll oscillating shaft 330 may be driven or operated as illustrated in the embodiments disclosed in Figs. 1 to 8 of the drawings.

In the modification illustrated in Fig. 10, a supporting tube 350 may be securely seated within a socket 352 formed on the transmission case with the tube 350 preferably extended substantially the length of the roll and located on the axis of the roll when the roll is in ironing relationship with the shoe. The outer end of the tube 350 carries an arm 353 which forms a guide and support for the outer end of a roll oscillating shaft 354, the end of the oscillating shaft 354 being provided with a crank 355 pinned to the shaft 354 and which crank 355 carries a bearing 356 similar to the bearing 336 and which forms a support for a bushing or sleeve 357 carried by the end plate 358 of the roll.

At the transmission end of the roll, there is secured within the end thereof a bearing member 359 which is journaled for rotation upon a bearing 360 carried by an oscillating plate 361 which is pinned to and supported by the oscillating shaft 354. The plate 361 is provided with a slot 362 through which the roll supporting tube 350 extends. The roll oscillating shaft 354 extends through a roll driving tube 363 which is journaled in a bearing 364 formed in a wall of a transmission case. Within the transmission, roll shifting mechanism like that illustrated in the embodiments disclosed in Figs. 1 to 8 may be provided for oscillating the shaft 354 in order to move the roll toward and away from the ironing shoe. The roll driving tube 363 at one end is provided with a pinion 365 which meshes with an internal gear 366 carried by the bearing member 359 and at the other end the roll driving tube 363 may be connected to be driven by roll driving mechanism like that illustrated in Figs. 1 to 8 inclusive of the drawings. In this case or in the case of the embodiments illustrated in Fig. 9, the roll driving tube and the roll oscillating shaft are concentrically arranged and located upon the axis of oscillation upon the roll while the roll supporting tube 350 is not so located. The tube 350 may be located upon the axis of rotation of the roll when the roll is in ironing engagement with the shoe, although this is not essential.

While the invention has been described with some detail, it is to be understood that the description is for the purpose of illustration only and is not definitive of the limits of the inventive idea. The right is reserved to make such changes in the details of construction and arrangement of parts as will fall within the purview of the attached claims.

55 I claim:

1. Ironing apparatus comprising a roll, a shoe,

a head for supporting said roll, means projecting into the roll and operatively connected thereto and driven from mechanism located within said head for swinging said roll to and from shoe engaging position, and a shaft operatively connected to said roll and driven from mechanism located in said head for rotating said roll about its own axis, said means and said shaft being arranged one inside the other on a common axis which is spaced from the axis of the roll.

2. Ironing apparatus comprising a roll and a plurality of cylindrical members projecting into said roll at one end thereof and lying one inside another on a common axis, one of said members constituting a part of a support about which the roll is swung, another of said members constituting a portion of driving means to swing the roll upon said support, and still another of said members constituting a part of means for rotating the roll about its own axis the axis of said roll being offset from said common axis.

3. An ironing machine comprising a shoe, a roll mounted for swinging movement into and out of operative ironing relationship with respect to said shoe, a power transmission located at one end of said roll, the other end of said roll being free, a tubular member extending from said transmission but parallel to and offset from the main axis of said roll and connected to said roll to swing the roll with respect to said shoe, means including a cylindrical member driven from said transmission and having a pinion for cooperating with an internal ring gear in said roll for rotating the roll, said tubular and cylindrical members having a common axis to maintain said pinion and ring gear in constant mesh.

4. An ironing machine comprising a base, a roll provided with bearings for rotation about its principal axis, a shoe supported from said base, a transmission case supported from said base, a cylindrical member extending from said transmission case and having its axis offset from and parallel to the principal axis of said roll, radius means connecting said cylindrical member and the bearings of said roll, means for rotating the cylindrical member to move said roll bearings through a curved path to swing said roll into operative or inoperative ironing position with respect to said shoe, and means for rotating said roll upon said bearings comprising a cylindrical member extending into said roll from said transmission case and having a pinion cooperating with a ring gear, said cylindrical members having a common axis to maintain said pinion and ring gear constantly in mesh.
